KEY CASE

Edgar N. Genovese, Baltimore, Md.

Application August 29, 1950, Serial No. 182,120

2 Claims. (Cl. 70—456)

1

This invention relates to key holders and more particularly to the type that offers protection or covering to the keys held thereby.

Included in the projects of this invention is the provision of a new and improved key holder that will avoid some of the disadvantages and limitations of the previous articles in this art.

Another object of the invention is to provide a new and improved key holder that will have means for holding keys in a casing that is readily opened for their projection therefrom without loosening them therefrom so they can become lost, or removed without the intention of the user.

A further object of the invention is to provide a new and improved key holder in box form that can carry keys within it in such a manner as to prevent them from cutting holes in the pockets in which they are carried.

An additional object of the invention is to provide a new and improved key holder that will be attractive in appearance, effective in operation, convenient to use, and simple in construction.

Other objects will become apparent as the invention is more fully set forth.

For a clearer understanding of the invention, and its objects, reference is made to the accompanying drawings, which in conjunction with the following description, illustrate a particular or preferred form of the invention, while the claims indicate the scope thereof.

In the drawings:

Figure 1 is a view in perspective of a closed key holder embodying this invention;

Figure 2 is a sectional view taken transversely through the holder, on line 2—2 of Figure 1, and

Figure 3 is a key holder open with key ring and keys available for use.

Similar reference characters refer to the same parts throughout the drawings.

The drawings illustrate a particular form of key holder comprising a casing made in two cup-like parts 10 and 11 termed arbitrarily the upper and lower parts and referred to as the "Covers," adapted to fit and align close up against each other. This is facilitated by a projection 12 along the front edge of the part 11, being offset as indicated in Figure 3, and arranged to lodge in the indentation 13 of front edge of the other part 10 as indicated, in Figures 2 and 3. A hole 14 somewhat elongated is provided in the main wall of the upper part or cover 10 for the placement of a rectangularly contoured wire key-ring 15 which is open where the legs 16 come together. This arrangement gives the ring a resilient clamp-

ing or closing tension permitting it to be opened up under pressure, and closing when the pressure is released. The lower part or cover 11 is likewise provided with an elongated hole 17 which aligns with the hole 14 when the parts or covers 10 and 11 are closed against each other. The legs 16 of the ring 15 pass through both holes 14 and 17 in the covers, and with the ring 15 in place and the projection 12 and indentation 13 align, hold the parts 10 and 11 resiliently together. The bars 18 of the ring are brought around the closed parts or covers 10 and 11 until the ring clamps them together as shown in Figures 1 and 2. When so positioned knobs 20 on the covers serve as locks to hold the ring 15 in that position, yet do not prevent the ring from swinging around as shown in Figure 3 and to be detached when desired. This is done by exerting a little pressure on the ring and springing it open enough to ride over the knobs 20.

Keys 19 are placed on the ring by opening it where the legs 16 abut and normally are closed in the casing. However by opening the casing and moving the parts or covers 10 and 11 so they will spread apart and slide along the ring 15 as shown in Figure 3, the keys 19 are exposed and projected so they can be used in the normal manner to open a lock. When not in use the keys 19 are returned to the casing and the covers 10 and 11 are closed back on them, followed by the rotation of the ring to lock them firmly together. The holes 14 and 17 are elongated in form to enable the ring to be slid along in it and permit the adjustment of the covers when they are moved to their open position, as well as enable the ring to be rotated laterally around the casing before the covers are opened up.

The device is simple, but designed for practical use. It is preferably made of light materials. The keys can be used for locking or unlocking the ignition for automobiles and other types of locks. When closed up the keys are retained out of the way and will not wear out the owner's pockets unnecessarily. The casing enables the keys to be easily used, and enables them to be found easily. The resilient ring has a double use. It not only holds the keys but serves as a lock to hold the covers together.

While but one general form of the invention is shown in the drawings and described in the specifications, it is not desired to limit this application for patent to this particular form, as it is appreciated that other forms of construction could be made that would use the same principles

and come within the scope of the appended claims.

Having thus described the invention, what is claimed is:

1. A key holder comprising two separate casing parts normally forming an enclosure for a key, each of the parts having an opening therein and the openings being in alignment with each other, a flexible, one-piece, rectangular key ring having its free ends in juxtaposition and extending through the aforesaid openings within the holder, said ring adapted to support a key at the junction of its free ends and said ring extending outwardly of and close to the walls of the two casing parts and normally maintaining said parts in closed position with the key between the parts, the parts being separable by sliding along two opposite sides of the ring engaging through the opening in each part, to release the key from the holder.

2. A key holder as set forth in claim 1 including knobs carried outwardly by each casing part to resiliently lock the key ring in place on the casing parts in normal closed position of the holder.
